Des. 203,751

PAGE 5

FIGURE 1 is a left side, top and front perspective view of a magnetic tape transport, showing our new design;

FIGURE 2 is a front elevational view;

FIGURE 3 is a rear elevational view; and

FIGURE 4 is a right side elevational view thereof, the opposite side being substantially a mirror image thereof.

The dominant features of our new design are shown in solid lines in the drawing.

We claim:

The ornamental design for a magnetic tape transport, substantially as shown and described.
